UNITED STATES PATENT OFFICE

BENJAMIN M. BISHOP, OF TERRE HAUTE, INDIANA, ASSIGNOR TO THE TERRE HAUTE PAPER COMPANY, OF TERRE HAUTE, INDIANA, A CORPORATION OF OHIO

CONTINUOUS BEATER FOR PAPER MAKING

Application filed October 7, 1929. Serial No. 397,990.

This invention is an improvement in continuous beaters for paper making, and more particularly in the arrangement and construction of screens for grading the paper stock.

One of the primary objects of the invention is to provide a screen, forming in effect a part of the tub wall, and continuous with said wall.

10 Another object is to provide a screen having openings of a character such that they are not readily clogged by the flowing pulp.

Another object is the provision of a deflector for directing the stock through the screen, 15 and means for adjusting the deflector to the required inclination with respect to the flow of stock.

Another object is the provision of mechanism for receiving the pulp as it passes 20 through the screen, and for discharging it into a plurality of chambers, with means for independently regulating the quantity flowing into each chamber.

With these and other objects in view the 25 invention consists in the construction and novel combination of parts fully described hereinafter, illustrated in the accompanying drawings, and pointed out in the claims appended hereto, it being understood that various changes in the form, proportion, size and minor details of construction within the scope 30 of the claims, may be resorted to without departing from the spirit of the invention.

In the drawings forming a part hereof:— 35 Fig. 1 is a longitudinal section of the improved beater.

Fig. 2 is a plan view with parts in section.

Fig. 3 is a section on the line 3—3 of Fig. 2.

40 Fig. 4 is an enlarged detail in section of the screen.

In the present embodiment of the invention, a tub 1 is provided of usual construction, being composed of a plurality of sections 1a, the sections having their edges abutted, as 45 shown. Within the tub is arranged a mid-feather 2, and a beater-roll 3, which is secured to a shaft 4, journaled in bearing pedestals 5 at the opposite side of the tub, and 50 driven in any usual or desired manner. The

beater-roll is provided with blades 6, and it cooperates with the usual bed-plate 7.

The back-fall 8 is arranged in rear of the bed-plate and beater-roll, and rearwardly of the back-fall a screen 9 is provided. This 55 screen constitutes one section of the tub wall, the said section being replaced by the screen, which is of a character to be presently described, and the screen is substantially continuous with the tub wall, being curved transversely to correspond to the curve of the wall, and being arranged vertically. The openings 10 through the screen 9, as shown in Fig. 4, are battered, that is, they flare toward the exterior of the tub. This provides for 60 free passage of the pulp, and prevents clogging of the opening.

Another deflecting plate 11 is mounted above the backfall, for deflecting the pulp which is moved up the front wall of the back-fall by 70 the beater-roll to the rear wall of the back-fall and to the screen. Another deflector plate 12 is hinged to the mid-feather, as at 13, and this deflector is adapted to be adjusted as regards its inclination to the flow of the 75 pulp, by means of a rod 14, connected at one end with the deflector, and extending through a bearing 15 on the tub wall.

A hand-wheel 16 is threaded onto the outer end of the rod, and by means of the wheel the 80 angle of the deflector with respect to the mid-feather, may be adjusted. The deflector 12 deflects the pulp from its rotary course in the beater through the screen 9, and the beaten pulp passes through the screen to a chamber 85 17, from which it may be drawn off when desired, by means of openings 18, controlled by gates 19, vertically movable in guides at the opening. The gates have rack edges, which are engaged by pinions 20, journaled on the 90 chamber wall. The openings 18 give access to chambers 21, which have outlets 22 for the pulp. By means of the gates 19, the stock from the chamber 17 may be thrown into one chamber 21, or into both, in equal proportions, 95 or in such proportions as may be elected. When both gates are closed, the flow of stock from the chamber 17 is stopped, and gradually filling up in the tub to the level of the beater, stops the operation thereof.

- In operation, the paper stock, together with the required amount of water, is continuously deposited in the tank, and the mass flows, or is moved by the beater-roll, in the direction indicated by the arrows. The stock is beaten up by the beater-roll and its cooperating bed-plate, and when beaten to the proper fineness, flows out continuously through the openings in the screen, while new stock is fed into the tub continuously, as needed.
- 10 The valves which control the flow from chamber 17 to chamber 21, are vertically movable gates. One or both of the gates is left open all of the time, so as to make the operation of the beater continuous and not intermittent. The stock is continually fed in and continually drained out through the extractor and through the gates or valves. The purpose of the gates is to enable the stock to be thrown to two machines by leaving both gates open, or to either machine by closing one of the gates and leaving the other open. The gates are so placed that when both are wide open, about equal quantities of stock go to each paper machine.
- 15 If it is desired to put two-thirds of the stock to one machine, and one-third to the other, one of the gates is partly closed, enough to pass the desired amount of stock for the one machine, the remainder going to the other machine. The stock is extracted through the extractor and goes to the paper machines, as fast as it is fed in to the beater.
- 20 What is claimed as new is:—
1. In a continuous beating machine, the combination with a tub having an enclosing wall, a mid-feather, a beater-roll and cooperating bed-plate, and a back-fall in rear of the beater-roll, of a screen interposed in the wall and forming a part thereof, and arranged rearwardly of the back-fall, said screen being curved transversely and so arranged that the pulp flowing over the back-fall impinges against the inner face of the screen, and a vertical deflector supported by the mid-feather in angular position for deflecting the pulp horizontally toward the screen.
- 25 2. In a continuous beating machine, the combination with a tub having an enclosing wall, a mid-feather, a beater-roll and cooperating bed-plate, and a back-fall in rear of the beater-roll, of a screen interposed in the wall and forming a part thereof, and arranged rearwardly of the back-fall, said screen being curved transversely and so arranged that the pulp flowing over the back-fall impinges against the inner face of the screen, and a deflector supported by the mid-feather for deflecting the pulp toward the screen, said deflector being adjustable to vary the inclination thereof with respect to the plane of the mid-feather.
- 30 3. In a continuous beating machine, the combination with a tub having an enclosing wall, a mid-feather, a beater-roll and coop-

erating bed-plate, and a back-fall in rear of the beater-roll, of a screen interposed in the wall and forming a part thereof, and arranged rearwardly of the back-fall, said screen being curved transversely and so arranged that the pulp flowing over the back-fall impinges against the inner face of the screen, and a deflector supported by the mid-feather for deflecting the pulp toward the screen, said deflector being hinged to the mid-feather to swing on a vertical axis, and means for moving the same and holding it in adjusted position.

4. In a continuous beating machine, the combination with a tub having an enclosing wall, a mid-feather, a beater-roll and cooperating bed-plate, and a back-fall in rear of the beater-roll, of a screen interposed in the wall and forming a part thereof, and arranged rearwardly of the back-fall, a chamber outside the tub and enclosing the screen into which the pulp flows from the screen, said chamber having a plurality of valve controlled ports, and a separate receiving chamber for the pulp from each port.

5. A pulp-beater of the class described, comprising a tub having an enclosing wall, a mid-feather, a beater-roll and cooperating bed-plate, and a back-fall rearward of the beater-roll, a screen rearward of the back-fall, a chamber enclosing the outer area of the screen and receiving pulp therefrom, a plurality of separate secondary chambers adjacent the one first named, with a port communicating between the first chamber and each secondary chamber, and an adjustable gate for each port to regulate relative amounts of pulp flowing to the respective secondary chambers, whereby pulp supply to a plurality of paper machines may be independently regulated.

Signed at Terre Haute in the county of Vigo and State of Indiana this 1st day of October A. D. 1929.
